US0D1083682S

(12) **United States Design Patent** (10) **Patent No.:** **US D1,083,682 S**
(45) **Date of Patent:** **** Jul. 15, 2025**

(54) **MOTORCYCLE**

(71) Applicant: **KAWASAKI MOTORS, LTD.**, Akashi (JP)

(72) Inventor: **Koji Kuwahara**, Akashi (JP)

(73) Assignee: **Kawasaki Motors, Ltd.** (JP)

(**) Term: **15 Years**

(21) Appl. No.: **29/918,294**

(22) Filed: **Nov. 27, 2023**

(30) **Foreign Application Priority Data**

May 29, 2023 (JP) ..... 2023-010837 D

(51) **LOC (15) Cl.** **12-11**

(52) **U.S. Cl.**

USPC **D12/110**

(57) **CLAIM**

The ornamental design for a motorcycle as shown and described.

DESCRIPTION

FIG. 1 is a front elevation view of a motorcycle showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front and left side perspective view thereof; and,

FIG. 8 is a rear and right side perspective view thereof.

The light-grayed-out portions in FIGS. 1 to 8, illustrating environmental structure of the claimed design, form no part of the claimed design.

1 Claim, 8 Drawing Sheets
